UNITED STATES PATENT OFFICE

ROBERT C. DANLY, OF CHICAGO, ILLINOIS, ASSIGNOR TO DANLY MACHINE SPECIALTIES, INC., OF CHICAGO, ILLINOIS, A CORPORATION OF ILLINOIS

FEEDING MECHANISM

Application filed February 1, 1930, Serial No. 425,172. Renewed September 3, 1931.

This invention relates to that type of feeding mechanisms in which an unfinished tappet roller or like piece of work is automatically fed into the grinding throat or zone of a centerless grinding machine, immediately following the ejection of a finished piece of work from said throat or zone. An example of which forms the subject matter of the patent to George I. Danly, No. 1,725,444, dated August 20, 1929. And this improvement has for its objects:

To provide a structural formation and combination of parts and mechanisms in an automatically operating feeding attachment for centerless roll grinding means, adapted to provide a simple and efficient handling of a piece of work from the supply hopper to the grinding throat or zone of the centerless grinding machine, with the mechanisms of the attachment coming to a stop with the completion of a single cycle of their movements, to be again started, on a succeeding finished work ejecting operation of said grinding machine.

To provide in the present type of automatic feeding attachments, means for providing a clear way through the same for pieces of finished work from the grinding throat of a centerless grinding machine, with the same involving a holding trough or cradle for a piece of unfinished work to be fed, arranged to have an initial movement out of the path of a finished piece of work as the same is automatically ejected from a centerless grinding mechanism, with a return of the trough or cradle to a normal position after the passage of said finished piece of work, in order that a piece of unfinished work in such trough or cradle may be properly fed into the grinding throat of the associated grinding mechanism.

To provide in such type of attachments, means whereby unfinished pieces of work are automatically positioned for proper delivery to the grinding throat of the grinding machine previous to such delivery, with such means involving a twin formation of receiving troughs or cradles hinged together in parallel relation, with one member arranged for an initial reception of a single piece

of work from a suitable single delivery supply means and receiving through associated operating mechanism, a tilting movement to discharge the contained piece of work into its companion trough or cradle from which the piece of work is pushed into proper position in the grinding throat of an associated grinding mechanism.

To provide in such type of attachments, means whereby single pieces of unfinished work on an inclined holding track are serially released, and fed along a horizontal extension of such track to an intermediate downspout arranged in the path of the travel of such pieces of work, in a delivery of the same to the grinding throat of an associated grinding mechanism. All as will hereinafter more fully appear.

In the accompanying drawings:

Fig. 1 is a perspective view illustrating the general arrangement of parts in the preferred form of the invention.

Fig. 2 is a side elevation of the attachment.

Fig. 3 is a detail vertical section on line 3—3 Fig. 4 of the mechanism for effecting the intermittent single cycle of movements of the invention.

Fig. 4 is a detail horizontal section, on line 4—4 Fig. 3.

Fig. 5 is a detail sectional plan view on line 5—5 Fig. 2.

Fig. 6 is a similar sectional plan view on line 6—6 Fig. 2.

Fig. 7 is an enlarged end elevation of the fixed work receiving trough and the companion tilting trough of the structure.

Like reference numerals indicate like parts in the several views.

As in the aforesaid Danly Patent No. 1,725,444, the feeding mechanism of this invention is more especially adapted for feeding in an automatic manner, headed cylindrical bodies, such as valve tappets, into proper position in the grinding zone or vale between the grinding wheel and the feeding wheel of an ordinary centerless roll grinding machine.

In the preferred arrangement of parts shown, the automatic feeding mechanism is carried on a hollow supporting base 1, in the

interior of which is mounted the hereinafter described operating mechanisms by which the interconnected feeding and other units are operated in proper sequence in each cycle of movements thereof.

The hollow supporting base 1 will usually house an electric or like motor (not shown), for imparting constant rotation to the driving shaft of the interconnecting mechanism above referred to. The base 1 carries a longitudinally extending bracket frame 2, forming a support for the hereinafter described mechanisms and parts by which pieces of unfinished work are serially guided and fed into the grinding throat or zone 1' of an associated centerless grinding machine. And in adjacent relation to said bracket frame 2, the base 1 is provided with a lug or ear 3 constituting a part of an attaching means whereby the present feeding attachment is rigidly connected to the frame of a centerless grinding machine in proper operative relation therewith.

At its upper end the base 1 carries a hopper 4 adapted to contain a supply of unfinished headed tappets or like pieces of unfinished work to be operated on, with said hopper provided with an oscillatory selector member or plate 5 adapted to lift, in serial order, pieces of unfinished work and place the same on an inclined track or guideway 6, down which the pieces of work are adapted to slide and be singly engaged and fed by the automatic feeding mechanism hereinafter described in detail. The construction and operation of the oscillatory selector plate or member 5 is substantially the same as that described in the aforesaid Danly Patent No. 1,725,444, the construction being such that in the case of a headed tappet or like headed article, the same will be selected and placed upon the inclined track or guideway 6 with its headed portion in a rearward position thereon.

Intermediate the length of the inclined track 6 and immediately above the same, a revoluble disk 7 is mounted, and with such disk provided with a series of radial blades 7', on its perimeter, with said blades adapted to engage the pieces of work lowermost on the track 6, and retard undue rapidity of descent of the same, while at the same time insure further descent of the same in single and successive order.

At its lower end the inclined track 6 is formed with a horizontal extension 6' onto which the pieces of work on the track are serially released, then moved along said track extension 6' and discharged into a downspout or boot 8 by the automatic release and feeding means hereinafter described. Said downspout or boot 8 is fixedly attached at the terminal end of said track extension 6'.

In the preferred construction shown, the downspout or boot 8 comprises a main stationary portion fixedly attached to the de-

livery end of the track extension 6' and a movable portion 8' hinged to the stationary portion as shown, with said movable portion provided at top with a tapering plate extension 9 which projects into the path of a passing piece of work on the track extension 6' so that a swinging or opening movement of the movable boot portion 8' will be effected by the passing piece of work to afford a free downward passage of the same through the downspout. The movable portion 8' of the downspout is normally held to its closed position by a spring 10, as shown.

In receiving relation to the lower or discharge end of the downspout 8, means are provided for receiving the pieces of work, and from such means the pieces of work are serially passed into the grinding throat of a centerless grinding machine, said receiving means comprising a construction as follows:

Said receiving means consists of a primary trough shaped member 11 and a secondary trough shaped member 12, hinged together in side by side relation with both of said members 11 and 12 pivotally mounted at one end to the end of the aforesaid bracket frame 2 of the main base 1 by a transverse pivot connection between the secondary member 12 and the end of said bracket. Such arrangement being adapted to permit of an upward tilting, by automatic means hereinafter described, of the members 11 and 12, in order to provide a clear way for a piece of finished work as the same is automatically pushed out of the grinding throat of an associated grinding machine.

In the construction shown, the primary work receiving member 11 is arranged in aligned receiving relation to the lower end of the downspout 8 heretofore described while the secondary receiving member 12 has proper aligned relation to the grinding throat of the associated grinding machine. In such construction the pintle of the hinge connection between said receiving members 11 and 12 has fixed connection with the primary receiving member 11, so that the same may receive through the operative connections hereinafter described with said pintle, an intermittent tilting movement, and with each tilting movement a piece of work in said member 11 will be discharged into the secondary receiving member 12, and in proper position to be pushed into the grinding throat of the associated grinding machine. Such pushing or feeding operation into the grinding machine is effected by a longitudinally reciprocating rod or plunger 13, preferably of the flexible coiled wire type, operatively attached by a coupling head 13' with the reciprocating bar 39 of the hereinafter described central control mechanism, as follows:

A central controlling mechanism, by which the operations of the series of mechanisms of this invention are set in action in regular and

proper sequence, comprises means as follows:

An endless screw shaft 14 is journaled longitudinally in the main base 1, is adapted to receive constant rotation by suitable operative connections with a driving motor arranged in said base. The endless screw or worm portion of the shaft 14 has operative engagement with a worm wheel 15 on a transversely arranged counter-shaft 16 with said counter-shaft carrying a gear wheel 17 which has suitable operative connection with the bladed disk 7 heretofore described.

In addition, the counter-shaft 16 has gearing connections 18, with the carrying hub 19 of the driving member of a clutch 20, with said hub 19 loosely mounted on a secondary counter-shaft 21. The carrying hub 22 of the driven member of the clutch 20 is mounted in a slidable manner by suitable spline and groove or like connection between said hub and counter-shaft, so that it may be moved into operative engagement with the hub 19, of the aforesaid driving member, to attain an intermittent revolution of said secondary counter-shaft 21 from the constantly rotating primary counter-shaft 16 during the existence of the clutch engagement of said hubs.

In the construction shown, the above mentioned intermittent engagement of the hubs 19 and 22 is automatically effected and maintained while a single complete revolution of the secondary counter-shaft 21 takes place, by a construction of parts as follows.

The carrying hub 22 of the driven clutch member is provided with a cam projection 23, preferably arranged in a peripheral channel in said hub as shown, with such cam projection arranged for operative engagement with an end portion of a locking bar 24, preferably of the sliding type, so that with an operative engagement of the cam projection against the end portion of the locking bar 24, the carrying hub 22 of the driven clutch member, of which the cam projection is a part, will be positively moved and held out of the above mentioned clutch engagement of the aforesaid carrying hubs 19, 22, until a release of the operative engagement between the cam projection and the locking bar is effected by a withdrawal of said locking bar from such engagement by means hereinafter described.

With a withdrawal of the locking bar 24 from such holding engagement with the cam projection 23, a spring 25 associated with the driven clutch member acts to move said driven clutch member into clutching engagement with the driving member of the clutch 20 to attain a succeeding single revolution of the driven member and its carrying shaft 22 aforesaid.

Automatic withdrawal of the locking bar 24 from engagement with the cam projection

23 above described, is attained by an operative connection thereof with a reciprocating part of the automatic work ejecting unit of an associated centerless grinding machine, and such connection preferably consists of an intermediate link 26 attached at one end to a convenient part of the work ejecting mechanism above referred to, and at the other end to a rock arm 27 on a transverse shaft 28 journaled in the bracket frame 2 of the main base 1, with said shaft 28 carrying a secondary rock arm 29 and a link connection 30 with the locking bar 24 aforesaid.

The primary counter-shaft 16 of the central controlling mechanism heretofore described carries on an end outside the main base 1, a crank arm 31 adapted to engage and operate the oscillatory selector plate 5 of the work containing hopper 4 before described.

The secondary counter-shaft 21 of the central controlling mechanism above referred to, carries a crank disk 32 the crank pin of which is connected by a link 33 to a crank arm 34 of a transverse rock shaft 35 journaled in the main base 1.

The end of the above described rock shaft 35 at a point exterior to the main base 1, carries a rock arm 36, which in turn is connected to and operates in serial order several of the automatic feeding units of the present feeding attachments, and as hereinafter set forth. With the described construction, the aforesaid rock arm 36 receives a full forward and a full backward stroke in each intermittent action of the central controlling mechanism heretofore described.

Midway its length, the rock arm 36 has operative connection with one end of an intermediate link 37, the other end of which is pivotally connected to a rock arm 38 on the journal hub of the aforesaid secondary work receiving member 12, the arrangement being such that as the rock arm nears the end of its backward stroke, the heretofore described tilting movement of the work receiving member 12, and parts moving therewith takes place so as to provide an unobstructed path for a piece of finished work as the same is automatically ejected from the grinding throat of the associated grinding machine.

The free end of the aforesaid rock arm 36 has operative connection with a reciprocating bar 39 moving in horizontal guides on the main base 1, with said bar 39 having operative connections with units of the present feeding mechanism, as follows:

Through the hereinafter described pushing contact stem 40 and intermediate mechanisms, impart a tilting movement to the primary work receiving member 11 to discharge therefrom a piece of the unfinished work into the secondary work receiving member 12.

Through a sliding head 41 fixedly attached to said bar 39 attain simultaneous operations of the work releasing mechanism and

work feeding mechanism that are associated with the inclined track or guideway as hereinafter described in detail.

The mechanism for imparting a tilting movement to the primary work receiving member 11 comprises a flexible shaft 42 one end of which is operatively attached to the journal pin of said primary member 11, while the other end of the shaft 42 is attached to a semi-rotary drum or hub 42' journaled in the bracket frame 2 of the main base 1, and formed with cam or spiral groove in its perimeter as shown in Fig. 6. Said cam or spiral groove is in operative engagement with a stud 43 on an operating bar 44 that has sliding movement on the aforesaid bracket 2, with its movement in one direction effected by a spring 45, with a positive movement in the other direction by pushing contact of the heretofore described stem 40 on the sliding bar 39 with the end of said operating bar 44, to attain a like positive semi-rotation of the drum or hub 42 and a tilting movement of the primary receiving member 11, as illustrated in Figs. 2 and 6.

The mechanism for effecting the serial release of the pieces of unfinished work on the inclined track 6 comprises a transversely swinging yoke 46 having an angular extension 46' by which it is pivotally attached to a fixed part of the main base 1.

At a point in the path of the pieces of work on the inclined track 6, the aforesaid swinging yoke 46 is provided with a pair of stop lugs or fingers 47 and 47' arranged in staggered and transversely spaced relation in the path of the pieces of work, with the lowermost lug 47' in a movement of the yoke 46 in one direction adapted to release an arrested piece of work and permit of its further descent along the track 6, while the uppermost lug or finger 47 in a movement of the yoke 46 in the opposite direction is adapted to release a succeeding piece of work and permit the same to move down into an arrested condition against the lug 47' with such alternate operations taking place in serial order during the operation of the mechanisms of the present apparatus.

Oscillation of the aforesaid transversely swinging yoke 46 is attained by a cam lug 48 on the aforesaid sliding head 41 carried by the sliding bar 39 aforesaid, with such cam lug in its movement in one direction adapted to have operative engagement with a stud or projection 50 on the aforesaid yoke 46 to attain a movement of the same in one direction, a movement of the yoke in the opposite direction being attained by a spring 51.

Subsequent to the work release just described, the mechanism for feeding the pieces of unfinished work along the horizontal track extension 6' and into the downspout or boot 8 comprises an arrangement of parts as follows:

An oscillatable plate 52 of an angular form is pivoted at 53 on the heretofore described reciprocating head 49, which is fixed on and moves with the sliding bar 39 from which other units of the present mechanisms receive motion. In the construction shown the forward and angular portion 52' of the plate 52 projects into the path of the pieces of work passing onto the horizontal track extension 6' and in the movement of the lowermost piece of work is displaced laterally to return behind said piece of work in its further passage along said track extension, and so that in a succeeding movement of the head 49 and plate 52, towards the discharge end of said track extension 6' the piece of work will be pushed along said track extension. During such movement along the track extension the piece of work will contact with the heretofore described tapering plate extension 9 of the movable side portion 8' of the downspout or boot 8 and attain a temporary enlargement of its passage and a ready descent of the piece of work, with the arrangement providing against the entry of more than one piece of work into said downspout at each operation of the mechanism.

The operation of the feeding mechanism is as follows:

With the parts in the position shown in Fig. 2, the operating arm 36 of the central control mechanism has moved from its normal position of rest to the left in said view, a distance to the right sufficient to lower the pair of work receiving troughs 11, 12 from their normal upwardly tilted position shown in dotted lines to the horizontal position for use shown in full lines in said view.

Such normal upwardly tilted condition of the troughs 11, 12 is for the purpose of providing a clear way for the passage of a piece of finished work from the grinding throat 1' of an associated grinding mechanism by the automatic work ejecting unit of the same.

In the inactive condition of the central control mechanism of the present construction, its locking bar 24 is in place upon the cam projection 23 of the driven clutch member 22, to maintain the same in its disengaged position, and in which condition of the mechanism, the operating arm 36 is in a position to the extreme left of its path of movement, ready for the commencement of an active cycle of movements of the same. In such position of the parts the work receiving troughs 11, 12 are in the heretofore described upwardly tilted condition shown in dotted lines in Fig. 2 for the purpose heretofore stated.

With an active operation of the finished work ejecting unit of a centerless grinding mechanism, the same, through its operative connection by link 26, will through the intermediate connections 27, 28 and 29, effect a withdrawal of the locking bar 24 from its engagement with the cam projection 23 of the

driven clutch member 22 and permit the same to move into operative engagement with driving clutch member 19, to start the control mechanism in a cycle of its movements, and through the heretofore described intermediate connections 21, 32 and 34 impart a rocking motion to the shaft 35 and the operating arm 36, swinging said arm first to the right and then back to the left or normal starting position of said arm.

The swinging movements of the operating arm 36 just described, is effected by a single revolution of the counter-shaft 21 which receives motion from the driven clutch member 22, and the stoppage of the mechanism at the end of said single revolution is effected by the cam projection 23 of the driven clutch member 22, riding up the end of the locking bar 24, and forcing said driven clutch member out of operative engagement with the constantly rotating driving clutch member 19. A period of rest then prevails until a succeeding cycle of operations are started in the manner heretofore described.

In the initial movement of the operating arm 36 to the right, the pair of work receiving troughs 11, 12 are lowered from their upwardly tilted condition shown in dotted lines in Fig. 2 to the approximately horizontal position shown in full lines in said view, through the intermediate connections 37 and 38 with the transverse pivotal mounting of said troughs on the main base.

Continued movement of said operating arm 36 to the right, through intermediate connections 39 and 13' will impart longitudinal movement to the rod or plunger 13 of the secondary receiving trough 13, to push a piece of unfinished work in said trough into the grinding throat 1' of an associated centerless grinding mechanism.

In the movement of said operating arm 36 to the left, the sliding bar 39 moving with the arm 36 and through the attached operating stud or tappet 40, has operative contact with the sliding bar 44 to move the same to the left and through the stud or pin 43 and spiral groove of the drum 42' impart a semi-revolution to the shaft 42, and through said shaft a tilting movement to the primary work receiving trough 11.

The above described tilting movement of the primary trough 11 towards the secondary trough 12 has for its purpose the transfer of a piece of work from the trough 11 into the trough 12, ready for delivery in the manner above set forth into the grinding throat 1' of a grinding mechanism.

In that the release mechanism comprising the parts 46, 47, 47', 48, 50 and 51, and the feeding mechanism, comprising the parts 52 and 52', are both operated through the sliding bar 39, by the movement of the operating arm 36 aforesaid, the serial operation of said mechanisms will take place in proper order,

as set forth in the description of parts in a preceding portion of the specification.

Having thus fully described my invention, what I claim as new, is:—

1. In a feeding mechanism of the type described, the combination of primary and secondary work receiving troughs pivotally mounted on the base of the mechanism, a hinge connection securing the troughs together in side by side relation, the secondary trough adapted for aligned relation with the grinding throat of a grinding mechanism, and the primary trough adapted for aligned relation with a supply source of unfinished work, means for imparting an upward tilting movement to said troughs, means for effecting a tilting movement of the primary trough towards the secondary trough, and a reciprocable plunger moving in the secondary trough and adapted to move a piece of work from the same into the grinding throat of a grinding mechanism.

2. In a feeding mechanism of the type described, the combination of primary and secondary work receiving troughs pivotally mounted on the base of the mechanism, a hinge connection securing the troughs together in side by side relation, the secondary trough adapted for aligned relation with the grinding throat of a grinding mechanism, and the primary trough adapted for aligned relation with a supply source of unfinished work, means for imparting an upward tilting movement to said troughs, means for effecting a tilting movement of the primary trough towards the secondary trough, and a reciprocable plunger having the form of a coiled wire shaft, moving in said trough to move a piece of work from the same into the grinding throat of a grinding mechanism.

3. In a feeding mechanism of the type described, the combination of primary and secondary work receiving troughs pivotally mounted on the base of the mechanism, a hinge connection securing the troughs together in side by side relation, the secondary trough adapted for aligned relation with the grinding throat of a grinding mechanism, and the primary trough adapted for aligned relation with a supply source of unfinished work, means for imparting an upward tilting movement to said troughs, means for effecting a tilting movement of the primary trough towards the secondary trough, the same comprising an intermediate shaft connected at one end to the pivot pintle of the primary trough, means for imparting intermittent semirotation to said shaft, and a reciprocable plunger moving in the secondary trough and adapted to move a piece of work from the same into the grinding throat of a grinding mechanism.

4. In a feeding mechanism of the type described, the combination of primary and secondary work receiving troughs pivotally

vibratory arm and at the other end to a rock arm on the transverse journal hub of the receiving troughs aforesaid, and a sliding bar having operative connection at one end with the vibratory arm and at the other end with the reciprocable plunger of the secondary trough.

10. In a feeding means of the type described, a central automatic control unit comprising a primary shaft having constant rotation, a counter-shaft in operative relation to said primary shaft, a driving clutch member loosely mounted on said counter-shaft and having gearing connection with said primary shaft, a driven clutch member having sliding engagement with said counter-shaft, a cam formation on said driven clutch member and acting to move and hold said driven clutch member in its disengaged position, 15 means for moving the driven clutch member into an engaged condition, a movable abutment bar having movement into and out of the path of the aforesaid cam formation and adapted to act in connection with said formation in moving and holding the driven clutch member in its disengaged condition, and in effecting a release from such disengaged condition, a vibratory operative arm having intermediate operative connections with said 20 counter-shaft to receive a forward and backward movement therefrom, said vibratory arm being adapted for operative connection with the feeding units of a work feeding mechanism.

35 11. In a feeding means of the type described, a central automatic control unit comprising a primary shaft having constant rotation, a counter-shaft in operative relation to said primary shaft, a driving clutch member loosely mounted on said counter-shaft and having gearing connection with said primary shaft, a driven clutch member having sliding engagement with said counter-shaft, a cam formation in said driven clutch member and 40 acting to move and hold said driven clutch member in its disengaged position, means for moving the driven clutch member into an engaged condition, a movable abutment bar having movement into and out of the path of the aforesaid cam formation and adapted to act in connection with said formation in moving and holding the driven clutch member in its disengaged condition, and in effecting a release from such disengaged condition, 45 a rock shaft in operative relation to said counter-shaft and having operative connection therewith through a crank arm on the counter-shaft, a link connecting the crank pin of said arm with a rock arm on said rock shaft, and a vibratory operating arm carried on said rock shaft.

50 12. In a feeding means of the type described, a central automatic control unit comprising a primary shaft having constant rotation, a counter-shaft in operative rela-

tion to said primary shaft, a driving clutch member loosely mounted on said counter-shaft and having gearing connection with said primary shaft, a driven clutch member having sliding engagement with said counter-shaft, a cam formation on said driven clutch member and acting to move and hold said driven clutch member in its disengaged position, means for moving the driven clutch member into an engaged condition, a movable abutment bar having movement into and out of the path of the aforesaid cam formation and adapted to act in connection with said formation in moving and holding the driven clutch member in its disengaged condition, and in effecting a release from such disengaged condition, means for imparting movement to said abutment bar in unison with the movement of the work ejecting means of a grinding mechanism, a vibratory operating arm having intermediate operative connections with said counter-shaft to receive a forward and backward movement therefrom, said vibratory arm being adapted for operative connection with the feeding units of a work feeding mechanism.

13. In a feeding means of the type described, a central automatic control unit comprising a primary shaft having constant rotation, a counter-shaft in operative relation to said primary shaft, a driving clutch member loosely mounted on said counter-shaft and having gearing connection with said primary shaft, a driven clutch member having sliding engagement with said counter-shaft, a cam formation on said driven clutch member and acting to move and hold said driven clutch member in its disengaged position, means for moving the driven clutch member into an engaged condition, a movable abutment bar having movement into and out of the path of the aforesaid cam formation and adapted to act in connection with said formation in moving and holding the driven clutch member in its disengaged condition, and in effecting a release from such disengaged condition, means for imparting movement to said abutment bar in unison with the movement of the work ejecting means of a grinding mechanism, the same comprising a link adapted for connection to said ejecting means, a rock shaft having crank arm connection with said link, a secondary crank arm on said rock shaft, and a link connecting said secondary crank arm with said abutment bar.

14. In a feeding means of the type described, a central automatic control unit comprising a primary shaft having constant rotation, a counter-shaft in operative relation to said primary shaft, a driving clutch member loosely mounted on said counter-shaft and having gearing connection with said primary shaft, a driven clutch member having sliding engagement with said

counter-shaft, a cam formation on said driven clutch member and acting to move and hold said driven clutch member in its disengaged position, means for moving the driven clutch member into an engaged condition, a movable abutment bar having movement into and out of the path of the aforesaid cam formation and adapted to act in connection with said formation in moving and holding the driven clutch member in its disengaged condition, and in effecting a release from such disengaged condition, a rock shaft in operative relation to said counter-shaft and having operative connection therewith through a crank arm on the counter-shaft, a link connecting the crank pin of said arm with a rock arm on said rock shaft, a vibratory operating arm carried on said rock shaft, means for imparting movement to said abutment bar in unison with the movement of the work ejecting means of a grinding mechanism, the same comprising a link adapted for connection to said ejecting means, a rock shaft having a crank arm connected with said link, a secondary crank arm on said rock shaft, and a link connecting said secondary crank arm with said abutment bar.

15. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, and a reciprocable plunger moving in the secondary trough and adapted to move a piece of work from the same into the grinding throat of a grinding mechanism.

16. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding mechanism.

ing throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said down-spout, means for imparting an upward tilting movement to said troughs, means for effecting a tilting movement of the primary trough towards the secondary trough, and a reciprocable plunger having the form of a coiled wire shaft, moving in said trough to move a piece of work therefrom into the grinding throat of a grinding mechanism.

17. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, the same comprising an intermediate shaft connected at one end to the pivot pintle of the primary trough, means for imparting intermittent semi-rotation to said shaft, and a reciprocable plunger moving in the secondary trough and adapted to move a piece of work from the same into the grinding throat of a grinding mechanism. 110

18. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grind- 115 120 125 130

ing mechanism and the primary trough adapted for aligned relation with said downspout, means for imparting an upward tilting movement to said troughs, a reciprocable plunger moving in said secondary trough for discharging a piece of work therefrom, and means moving in unison with the reciprocable plunger for effecting a tilting movement of the primary trough towards the secondary trough.

19. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, the same comprising an intermediate shaft connected at one end to the pivot pintle of the primary trough, a spirally grooved drum connected to the other end of said shaft, a sliding bar having stud engagement with the spiral groove of said drum, and a reciprocable plunger moving in the secondary trough and adapted to move a piece of work from the same into the grinding throat of a grinding mechanism.

20. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough to-

wards the secondary trough, the same comprising an intermediate shaft connected at one end to the pivot pintle of the primary trough, a spirally grooved drum connected to the other end of said shaft, a sliding bar having stud engagement with the spiral groove of said drum, a reciprocable plunger moving in the secondary trough and adapted to move a piece of work from the same into the grinding throat of a grinding mechanism, and means moving in unison with said plunger for imparting intermittent movement to said sliding bar.

21. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, a reciprocable plunger moving in the secondary trough and adapted to move a piece of work from the same into the grinding throat of a grinding mechanism, and a central automatic control mechanism having starting connection with the work ejecting mechanism of a centerless grinding mechanism and adapted to make a complete revolution, a vibratory arm receiving a forward and rearward movement from said control mechanism, and operative connections between said arm and the upward tilting means of the work receiving troughs and between said arm and the plunger of the secondary receiving trough.

22. In a feeding mechanism, the combination of a main base, a work containing hopper, a selector mechanism associated with said hopper, an inclined track adapted to receive pieces of work from said selector mechanism, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the machine base, a hinge connection securing the troughs together in side by side re-

- lation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, a reciprocable plunger moving in the secondary trough and adapted to move a piece of work from the same into the grinding throat of a grinding mechanism, and a central automatic control mechanism having starting connection with the work ejecting mechanism of a centerless grinding mechanism and adapted to make a complete revolution, a vibratory arm receiving a forward and rearward movement from said control mechanism, a link attached at one end to the mid-length of said arm and at the other end to a rock arm on the transverse journal hub of the aforesaid receiving troughs, and operative connections between said arm and the aforesaid reciprocable plunger.
23. In a feeding mechanism, the combination of a main base, a work containing hopper, a selector mechanism associated with said hopper, an inclined track adapted to receive pieces of work from said selector mechanism, means for retarding and feeding the work in its downward passage on said track, the same comprising a revoluble disk having peripheral blades adapted to engage the pieces of work, a fixed receiving downspout at the lower end of said track, means for serially feeding pieces of work from said track into said downspout, means for feeding the pieces of work from said downspout into the grinding throat of a grinding mechanism, the same comprising primary and secondary work receiving troughs pivotally mounted on the main base, a hinge connection securing the troughs together in side by side relation, the secondary trough being adapted for aligned relation with the grinding throat of a grinding mechanism and the primary trough adapted for aligned relation with said downspout, means for imparting an upward tilting movement to said troughs, means for effecting a tilting movement of the primary trough towards the secondary trough, and a reciprocable plunger moving in the secondary trough and adapted to move a piece of work from the same into the grinding throat of a grinding mechanism.

In testimony whereof I hereunto affix my signature.

ROBERT C. DANLY.
